DAVENPORT COUCH

James J. Gervasio and Victor J. Bergstrom, Chicago, Ill., assignors to Superior Felt & Bedding Company, a corporation of Illinois

Application December 14, 1936, Serial No. 115,773

7 Claims. (Cl. 5—44)

The present invention relates to that type of davenport bed or couch in which there is a back, and has for its object to produce a simple and novel construction in which the back is shifted so as to lie entirely below what may be termed the top of the bed when the couch is opened up and ready for use as a bed.

A further object of the present invention is to produce a simple and novel couch of the davenport type in which there is a sturdy, substantial back serving as such when the couch is closed and adapted to serve as a mattress-supporting member when the couch is opened.

A further object of the present invention is to produce a simple and novel couch or bed of the davenport type in which the relative opening and closing movements between the seat section and an underlying section are brought about by swinging movements of a back member from a more or less upright position.

A further object of the present invention is to produce a simple and novel couch or bed of the davenport type in which there is a back mounted on the couch section that underlies the seat section, which back serves as a lever to produce the relative opening and closing movements of the two sections and also as a mattress support for the seat section on which it is mounted.

The various features of novelty whereby our invention is characterized will hereinafter be pointed out with particularity in the claims; but, for a full understanding of our invention and of its objects and advantages, reference may be had to the following detailed description taken in connection with the accompanying drawings, wherein:

Figure 1 is an end view of a couch constructed in accordance with the present invention, only the framework appearing, and the mattresses and pillows being indicated in dotted lines; Fig. 2 is a vertical section taken on a plane extending from front to rear, showing the couch in its closed condition, as in Fig. 1; Fig. 3 is a view similar to Fig. 2, showing the couch opened, with the mattresses indicated in dotted lines; Fig. 4 is a top plan view of the stripped framework, showing the couch closed as in Figs. 1 and 2; Fig. 5 is a view similar to Fig. 4, showing the couch opened, as in Fig. 3; Fig. 6 is a section, on a larger scale, on line 6—6 of Fig. 4; Fig. 7 is a side elevation, on the same scale as Fig. 6, showing a fragment of the couch in its open condition; Fig. 8 is a section on line 8—8 of Fig. 7; Fig. 9 is a view similar to Fig. 2, showing only parts of the couch and a modified form of actuati-

ing mechanism between the couch back and the seat section; Fig. 10 is a section on line 10—10 of Fig. 9; and Fig. 11 is a top plan view of a couch in which there are two independent sets of opening and closing mechanisms near the two ends instead of a single central mechanism, the couch being open and only so much as is necessary for an understanding of the said mechanism being shown; and Fig. 12 is a section on line 12—12 of Fig. 11.

Referring to Figs. 1 to 8 of the drawings, 1 represents the rigid framework of the seat section of a davenport couch, provided with any suitable mattress-supporting means which, in the arrangement shown, is indicated diagrammatically as a metal fabric 2. The framework 1 may be supported at the four corners upon casters 3. The rear side of the seat section is open to permit this section to serve as a housing for a secondary or under section when the couch is closed. The second or under section also comprises a metal framework, the same being of a size to pass in and out through the open rear side of the seat section; and comprises a horizontal bottom frame 4, two front corner posts 5, 5 and two rear corner posts 6, 6 which extend upwardly and rearwardly from the bottom frame 4. The upper end of each front corner post is connected to the corresponding inclined rear post by a track or rail 7 which may conveniently comprise an angle iron 30 one of whose flanges is horizontal, while the other flange extends upwardly from the horizontal flange. The top of the frame of the seat section is provided with rollers or casters 8 that rest upon the rail 7 and are adapted to run along 35 the same and be guided thereby as the seat section is moved to open or close the couch.

Extending between the upper ends of the inclined rear corner posts or legs 6 is a rectangular back frame 9. Hinge pins 10 extend through the upper ends of the posts or legs 6 and the end bars of the frame 9 a short distance from the lower longitudinal bar 11 of the latter frame. The frame 9 thus serves to connect the upper ends of the rear corner posts or legs together and, when 45 the frame is swung about its hinged axis, the upper longitudinal bar 12 thereof moves in one direction while the lower bar moves in the opposite direction. This swinging movement of the back frame is utilized to move the upper or outer seat 50 section in and out in the closing and opening of the couch; the under section being supported in any suitable way on the floor, so that it will remain stationary while the seat section moves. Thus, the under section may be provided with 55

feet 13 instead of casters, whereby frictional resistance is offered to shifting movements of the under section.

The two couch sections are connected by an arrangement of levers and links. In the arrangement shown, there are two long arms or levers 14 and 15 connected to the forward portion of the under section by a vertical hinge pin 16 passing through their overlapped ends. This connection with the under-frame is situated midway between the two ends of the couch; the hinge pin conveniently extending down into or through a block or post 17 mounted upon a crosspiece 18 extending between and secured to the front and rear members of the frame 4. On the part 18, in front of the support 17, is an upwardly projecting pin or stub 19 encased in a rubber sleeve 20, which serves as a cushioning stop to limit the swinging movements of the levers or arms 14 and 15 toward each other. The free ends of the members 14 and 15 are connected to the front of the seat section frame structure by means of links 21 and 22 that are considerably shorter than the members 14 and 15; the connections between the links 21 and 22 being toward the ends of the seat section. Normally, when the couch is closed, the members 14 and 15 extend approximately in the longitudinal direction, their free ends being somewhat farther back than the hinge connection. When the couch is opened, the members 14 and 15 swing forwardly, far past center, and the links 21 and 22 come almost into alignment with them, as shown in Fig. 5. A tension spring 23 connects together the members 14 and 15 a short distance from the hinge axis. When the couch is closed, this spring lies behind the hinge axis and, upon the opening of the couch, the spring moves forward until it lies well in front of the hinge axis. Consequently, the spring tends to hold the members 14 and 15 in whichever extreme position they may be occupying. Also, as the spring passes from one side of the hinge axis to the other, it begins to cooperate with the forces that are causing the movements of the members 14 and 15, and thus assist in completing such movements.

Rising from the rear portion of the crosspiece 18 of the frame 4 is a U-shaped bracket 24 to the arms of which are pinned a pair of rocker members 25 and 26; the connections between the rockers and the bracket being rivets 27 or other suitable devices, passing through the rockers midway between their ends and holding the rockers securely upon the bracket while permitting them to swing in parallel vertical planes extending from front to rear. One arm of the rocker 25 is connected to the member 14 by a rod or strut 28, while the corresponding end of the rocker 26 is connected to the member 15 by a part 29 similar to the part 28. The other ends of the rockers are connected to a yoke 30 provided with a stem 31 that extends rearwardly to the lower bar 11 of the back frame, where it is connected to a bracket 32 by a rivet 33 or other device serving as a hinge pin.

Normally, when the couch is closed, as shown in Figs. 1, 2 and 4, the two rocker members 25 and 26 stand with their upper ends thrust forward and their lower ends, to which the struts or rods 28 and 29 are connected, lying toward the rear of their hinge axis 21. When the upper or main portion of the back member is swung forward, the bottom longitudinal bar 11 thereof 75 swings toward the rear, turning the rocker mem-

bers in the clockwise direction, as viewed in Figs. 2 and 3, and causing the lever members 14 and 15 to be swung forwardly. Such movement of the members 14 and 15 can take place only along with a forward movement of the seat section of the couch and, therefore, the swinging down of the back forces the seat section forward and brings about the opening of the couch. Conversely, when the back member is swung up again, it draws the seat section back over the bottom 10 or underlying section. It will be seen that as the seat section approaches the limit of its forward movement, the members 14 and 15 close on the cushioning stop which acts as a buffer to slow down the movement of the seat section and bring 15 it gently to rest. So, also, in closing the couch, suitable buffer means may be provided to absorb the shock of the final closing. In the arrangement disclosed, as best shown in Fig. 6, each of the rails or tracks 7 has at its rear end an upwardly projecting cushion 34 against which the corresponding roller 8 on the seat section strikes at the rearward limit of movement of the seat section. Furthermore, each of the tracks or rails 7 may have thereon a hump 35 over which the corresponding roller 8 must pass before it engages the cushion; these humps being preferably so placed that they hold their rollers against the cushions and thus serve yieldingly to lock the 30 two couch sections together.

Not only does the back member of the couch serve as an operating lever for opening and closing the couch, but it also constitutes the mattress supporting means for the under section. The end members of the back frame are farther apart than the tracks or rails 7, so that when the back is swung down, these end members lie outwardly from the tracks or rails. Suitable supporting elements are provided on the bottom section to hold up the front end of the back when the back is in a horizontal position. In the arrangement shown, the parts are so proportioned that the horizontal flanges of the end bars of the back frame rest on top of the front legs 5 of the bottom couch section when the back is horizontal. This construction insures that the back is firmly supported in its horizontal position and, by providing the back frame with a suitable mattress-supporting spring, the under section of the couch serves as a comfortable bed when provided with a mattress in the usual way. As in the case of the seat section, we have shown the back frame as being simply provided with a metal fabric 36 on which the mattress may rest.

The parts of the couch, including the back, may be suitably upholstered. We have not attempted to illustrate any upholstering since the present invention is concerned only with the skeleton of the couch, or what might be termed 60 the fixtures. It may be noted, however, that the couch may have two overlying cushions or mattresses, such as indicated in dotted lines at A and B in Fig. 1, the upper one of which, at least is loose. There may also be the usual pillows, 65 indicated in dotted lines at C. When the couch is opened, the pillows are temporarily discarded and the mattress B is laid upon the horizontal back member, as illustrated in Fig. 3.

In order to prevent the back from making a 70 noise when it is swung down quickly, we prefer to provide it with cushioning pads 37, as best shown in Figs. 7 and 8, at the points where it rests upon the upper ends of the legs 5 or other supporting shoulders or seats that may be pro- 75

vided. If the back is slammed down, these cushions will absorb the shocks and make it unnecessary to depend upon the upholstering to deaden the sounds.

5 It should also be noted that when the couch is closed and is being used by persons seated thereon, leaning against the back does not tend to push the seat section forward as is the case in older types of couches; but the greater the 10 backward pressure on the back, the greater will be the force holding the seat section in its closed position. Consequently, the back may be said to have a third function, in addition to the two heretofore described, namely, that of utilizing 15 the stresses set up by a person seated on the couch and leaning against the back, to lock the seat section in its closed position.

In Figs. 9 and 10 we have illustrated a somewhat different actuating means between the back 20 member and the lever members 14 and 15, than that illustrated in the other figures. In this modified arrangement, the struts 38 and 39 correspond to the members 28 and 29 in the other form. These extend back to a slide 40 at the 25 upper end of which are rollers 41 running horizontal, parallel, channel-shaped guides or rails 42 arranged at right angles to the front and rear of the couch. The guides or rails are mounted on parallel bars 43, 43, corresponding to the bar 30 18 in the first form, extending from the front member of the frame 4 to the rear member. The slide 40 is joined to the back member 44 by a strut or connecting rod 45 which is pinned to the frame of the back member, as at 46, above 35 the hinge axis 10 of the back member. Therefore, when the back is swung down, the slide 40 is pushed forward, causing the couch to open and, when the back is swung up again, the slide is retracted and the seat section is drawn back 40 into its closed position. In this modified arrangement, the back member lies at a somewhat lower level than in the other form, and therefore, it will ordinarily be provided with a 45 mattress-supporting spring structure projecting beyond the rear face, as indicated in dotted lines at 47. Therefore, when the back member is in its horizontal position, it presents a mattress-supporting surface extending up to the proper level.

In Figs. 11 and 12 there is illustrated a construction quite similar to that of Figs. 1 to 8 except that there are two operating mechanisms, one at each end of the couch, instead of only a single mechanism. Since the two mechanisms at opposite ends of the couch are alike except that one is right and the other is left, only one need be described in detail. Referring to the mechanism at the lefthand end of Fig. 11, 50 and 51 are two long bars or links and 52 a short one pinned together end to end, one terminal of the 55 assembly being pinned to an ear 53 on the rear bar of the frame 4 and the other terminal being pinned to an ear 54 on the rear part of the seat section frame 1. When the couch is open, as indicated in Fig. 11, the distance between the 60 ears 53 and 54 is less than the overall length of the assembled members 50, 51 and 52, so that the latter do not lie in a straight line. A tension spring 55 connected between the member 50 and the rear longitudinal bar of the frame 4, tends 65 to swing the member 50 into parallelism with that bar and thus pull back the seat frame when the latter is in a forward position. There is a lever 56 connected at one end to the bar or link 51 at about the middle of the latter and at the other end to an ear 57 on the adjacent side bar

of the frame 4. The lever 56 is positively moved by suitable connections with the couch back 9. In the arrangement shown, there is a post 58 rising from the rear bar of the frame 4 near the corner of the couch. A rocking lever 59 is pinned 5 to this post, at a point between its ends, so as to be capable of swinging in a vertical plane forwardly and rearwardly of the couch. A link 60 connects the upper end of the rocking lever 59 to the bottom bar 11 of the couch back. A 10 connecting rod 61 joins the lower end of the rocking lever 59 to an intermediate point on the lever 56.

Assuming the couch to be open, as illustrated in the drawings, the raising of the back frame 9 15 into its normal, more or less upright position, swings the rocker lever 59 in the counter-clockwise direction as viewed in Fig. 12, thereby causing this lever to pull back on the connecting rod 61 and produce a folding action of the links 20 or bars 50 and 51; this folding action resulting in drawing back the seat section of the couch until it overlies and covers the secondary or under couch section. To open the couch again, the back is swung forwardly and down, causing the 25 lever 59 to swing in the clockwise direction as viewed in Fig. 12 and the link or bar assemblage between the ears 53 and 54 to be unfolded and partially straightened; whereby the seat section is thrust forward and uncovers the underlying 30 section.

The two mechanisms at opposite ends of the couch operate in unison and thereby bring about an equalization in the application of forces to and in the movements of the two ends of the 35 seat section. In other words, the opening and closing movements of the couch are smooth and even, and there is no tendency to cramp or bias the seat section in a manner to prevent easy operation or perfect positioning of the couch 40 sections during and at the end of an opening or closing operation.

The pins 62 which connect together the links or bars 51 with the corresponding links or bars 52, are easily detachable, whereby the two sections of the couch may be disconnected, upon the removal of these pins; thereby providing two independent single beds. In the arrangement shown, the pins 62 have knobs or heads on their 45 upper ends by which they may be grasped and 50 lifted out of their working positions when it is desired to disconnect the two couch sections from each other.

In the first form of the couch, the seat section is provided with rollers 8 that run upon tracks 55 or rails 7 on the under section. In the couch of Figs. 11 and 12 the rollers are on the under section and the tracks on the seat section. The tracks or rails 63, 63 on the seat section extend from front to rear in the plane of the top 60 of the framework 1. These elements may conveniently be angle irons one of the flanges of each of which is horizontal while the other flange extends downwardly from the horizontal flange. The rollers 64 are mounted on the outer ends of 65 short arms or brackets 65, 65 projecting forwardly from the front side of the frame of the under section; the parts being so located that the rollers underlie the horizontal flanges of the tracks or rails. The extreme rear ends of the 70 horizontal flange of each track or rail is bent downwardly, as at 66, to produce a hook-like construction that will cause the forward movement of the seat section to be arrested when the rollers reach the rear ends of the tracks or rails. When 75

it is desired to disconnect the two sections from each other, the rear side of the seat section must be raised slightly, after the pins 62 have been pulled, to disengage the hooked ends of the tracks or rails from the rollers.

5 While we have illustrated and described with particularity only a single preferred form of our invention, with a few modifications, we do not desire to be limited to the exact structural details thus illustrated and described; but intend 10 to cover all forms and arrangements which come within the definitions of our invention constituting the appended claims.

We claim:

15 1. A piece of furniture comprising a seat section and an underlying second section of only slightly lesser height than the seat section adapted to be exposed when the seat section is shifted forward, a back member hinged to and adapted 20 to be swung forward and rest upon said second section, lever means connecting said sections together, and operating devices connecting said lever means and said back member together to cause said seat section to be moved forward when the back section is swung forward and downwardly.

2. A piece of furniture comprising a seat section and an underlying second section of only slightly lesser height than the seat section, guide 30 rails extending from front to rear on said second section, rollers on the rear end of the seat section resting on said guide rails, equalizing lever mechanism connecting said sections together, a movable back member on and adapted to be 35 shifted into a position in which it rests on and serves as a mattress supporting member for said second section, and means actuated by said back member to operate said lever mechanism to move said seat section when the back is moved.

40 3. A piece of furniture comprising a seat section and an underlying second section adapted to be exposed when the seat section is shifted forward, a back member hinged at its lower end to the rear end of the said second section and adapted to be swung from a more or less upright 45 position to a lowered horizontal position in which it rests upon and serves as a mattress support for said second section, and connections between said back member and said seat section to cause the latter to be moved forward when the back member is swung down from the upright to the horizontal position, said connections including a pair of levers having a hinge connection between corresponding ends and the front part of said second 50 section midway between the ends of the latter

55 and links connecting the other ends of said levers to the seat section near the ends of the latter.

4. A piece of furniture comprising a seat section and an underlying second section, guide rails extending from front to rear on said second section, 5 rollers on the rear end of the seat section resting on said guide rails, equalizing lever mechanism connecting said sections together, a back member hinged at its lower end to said second section and adapted to be swung forward to rest 10 upon the latter section, means actuated by said back member to operate said lever mechanism to move said seat section when the back is moved, and cushion means to absorb the shocks incident to stopping the seat section at the limits 15 of its movements relative to the second section.

5. A piece of furniture comprising a seat section and an underlying second section, guide rails extending from front to rear on said seat section, 20 rollers on the front end of the second section engaged with said guide rails, equalizing lever mechanism connecting said sections together, a back member hinged at its lower end to said second section and adapted to be swung forward and rest upon the latter section, and means actuated by said back member to operate said lever mechanism to move said seat section when the back is moved.

6. A piece of furniture comprising a seat section and an underlying second section of only 30 slightly lesser height than the seat section, guide rails extending from front to rear on one of said sections, rollers on one end of the other of said sections engaged with said guide rails, equalizing lever mechanism connecting said sections 35 together, a movable back member on and adapted to be shifted into a position in which it rests on and serves as a mattress supporting member for said second section, and means actuated by said back member to operate said lever mechanism to 40 move said seat section when the back is moved.

7. A piece of furniture comprising a seat section and an underlying second section, guide rails extending from front to rear on one of said sections near the top thereof, rollers on the other 45 of said sections engaged with said guide rails, equalizing lever mechanism connecting said sections together, a back member hinged at its lower end to said second section and adapted to be swung forward and rest upon the latter section, and means actuated by said back member to operate said lever mechanism to move said seat section when the back is moved.

JAMES J. GERVASIO.
